UNITED STATES PATENT OFFICE.

CHRISTIAN L. BERGER, OF BOSTON, MASSACHUSETTS.

COMPASS.

1,115,774.

Specification of Letters Patent.

Patented Nov. 3, 1914.

Application filed February 29, 1912. Serial No. 680,753.

To all whom it may concern:

Be it known that I, CHRISTIAN L. BERGER, a citizen of the United States, and resident of Boston, in the county of Suffolk and State of Massachusetts, have invented an Improvement in Compasses, of which the following description, in connection with the accompanying drawings, is a specification, like letters on the drawings representing like parts.

This invention relates to a compass such as is ordinarily employed in surveyors' transits and like instruments. The compass in such an instrument comprises a magnetic needle mounted in a shallow circular inclosure having a glass top, and having means to lift the needle off its pivot to hold it in any fixed position and to prevent wearing down the pivot when the instrument is not in use. Within such inclosure and underneath the glass is also usually arranged a plate having marked thereon the indications for degrees, and such plate is usually loosely contained within the inclosure so that it may be shifted or set to adjust the compass for magnetic variation either to east or west of true north as required for the particular locality where the instrument is being used. This plate is termed the "variation ring," and is preferably made with a short portion or segment having teeth cut therein which are arranged to mesh with a pinion on the outside of the inclosure in a convenient position to be operated to adjust the "variation ring." The means or the "lifter" to raise the needle off its pivot projects through an opening in the inclosure, at a different point from the opening provided for the "variation ring" setting device, and the outer end of the lifter is engaged by a cam or screw to be depressed thereby and thus to raise the inner end, and lift the needle off its pivot. This former construction has been found to be very objectionable and defective in that two openings into the inclosure were necessitated, through which openings dust easily penetrated to such an extent that the openings were frequently clogged, thus impairing the operation of the "lifter" and the adjustment of the "variation ring," as well as affecting the sensitiveness of the instrument and dulling the pivot and also clouding the glass. A still further objection to such a construction wherein openings were formed

into the needle inclosure is that moisture, rain, or snow would easily drift in and consequently might rust the pivot of the needle as well as the needle itself, and thus seriously affect the accuracy of the compass.

It is an object of this invention to improve and perfect such compasses by preventing the entrance of dust or moisture into the inclosure where the needle is mounted, and thus to eliminate all danger of impairing the sensitiveness and accuracy of the needle through such clogging or rust of the needle or its pivot.

It is also an object of the invention to provide means to adjust the variation ring and to operate the needle-lifter at the same point, and also to protect both the opening for the needle-lifting means and the opening for the variation setting means by a single protecting device.

A further object of the invention is to provide a combined protecting device, variation setting means, and needle-lifting means which may be easily attached to any existing surveyors' compass.

Further objects of the invention, details of construction, and combinations of parts will be hereinafter more particularly described and claimed.

Referring to the drawings, wherein a preferred embodiment of the invention is illustrated, Figure 1 shows in plan view a surveyor's compass such as is usually provided in a transit, the drawing showing a portion of the covering glass broken away; Fig. 2 is a view, partly in cross-section, on the line 2-2 of Fig. 1; Fig. 3 is an enlarged detail view partly in section of the protecting device affixed to the compass outside of the needle inclosure and containing both the means to operate the needle-lifter and to adjust the variation ring; and Figs. 4 and 5 show views in elevation and partly in section of modified forms of the means to operate the needle lifter and to adjust the variation-ring.

1 is the base of a compass box formed in the usual manner, with an upstanding flange 2 and an annular margin 3. Fitting closely to the flange 2 and resting on the margin 3 is a circular ring 4 having a shelf 5 on which the glass 6 rests. Preferably the inner top portion of the ring 4 is threaded, and a covering retaining ring 7 is arranged to screw into said threads to clamp the glass

6 between the lower surface of the ring 7 and the flange 5. A steel pivot 8 is affixed to a plug 9 threaded through the central aperture in the base 1 in the usual manner, and mounted to swing on this pivot is the needle 10. Resting loosely on the flange 2 is a variation ring 11 on which may be marked the degrees of the circle in usual manner. A segment of this ring 11 is formed with teeth, as indicated at 12, and the ring 11 is capable of being slid on the flange 2 by suitable manipulation of a gear outside the inclosure meshing with the toothed segment 12, as will be described. In order to lift the needle 10 off its pivot, a lifter 13 of usual form is provided, which lifter projects through a suitable aperture 14 in the flange 2 extending outside the inclosure and over the marginal portion 3 of the compass base. Preferably, and as herein shown, the lifter 13 extends through the flange 2 underneath a portion of the toothed segment 12 in the variation ring, and preferably also the gear to operate said variation ring extends through an aperture in the flange 2 directly over that through which the lifter 13 projects. This construction enables the means to operate the lifter and the means to adjust the variation ring to be arranged at the same point on the outside of the needle inclosure, and also enables a single protecting device to cover both the apertures through the flange 2 and ring 4.

The protecting device preferably comprises a cup-shaped member 15 which may be secured to the marginal portion 3 of the base by suitable screws, as shown in Fig. 1, said member fitting closely against the outside of the upstanding ring 4, a portion of said member being cut away as indicated at 16 in Fig. 1, to more closely fit the ring 4 and to cover the entire width of the opening through which the gear to operate the variation ring must pass, as will be readily seen on reference to Fig. 1. Preferably also the member 15 is arranged to contain the means to operate both the lifter and the variation ring, said member having its lower portion threaded, in which a plate 17 is adapted to be screwed, said plate having a hub 18 threaded to receive the stem 19 of a thumb screw 20, which stem engages the projecting outer end of the lifter 13, as clearly shown in Fig. 3. Manipulation of the thumb screw 20 acts to oscillate the lifter 13 and to raise and lower the needle 10. Surrounding the hub 18 and resting upon the plate 17 is positioned the gear 21, which gear is in mesh with the toothed segment 12 of the variation ring. This gear 21 is formed with an upstanding hub 22 projecting above the member 15 and having a plurality of spanner holes 23 so that the gear may be easily rotated to adjust the

variation ring 11. Preferably a spring 24 is interposed between the top of the gear 21 and the roof of the member 15.

In operating the devices just described, the needle may be independently raised from its pivot, and the variation ring may be independently adjusted to any desired position from the same point or side of the compass, as shown. This construction is of considerable advantage, saving the operations formerly required of making such adjustment from different and usually opposite points of the compass, which necessitated the operator either moving around the compass or reaching across its face. The protecting member 15 covering both apertures in the needle inclosure through which the adjusting mechanism must work absolutely prevents the entrance of dust and the consequent clogging of the mechanism, and also prevents the entrance of moisture, rain, or snow, and consequently eliminates the danger of rust spoiling the pivot or the needle 10 and impairing the efficiency and sensitivity of the compass thereby. It will be noted that in the preferred construction herein illustrated, the thumb screw 20 is mounted concentrically with the gear 21 and with the hub 18, although such an arrangement is not necessary and the invention is to be understood as not limited to this form. A further feature in the preferred form herein shown is that the top 20 of the thumb nut overhangs and protects the upstanding portions of the hubs 22 and 18, thus serving as a further means of preventing moisture from penetrating into the interior of the member 15 or of the needle inclosure.

The advantages incident to this construction will be readily apparent, as the sensitivity and accuracy of such a compass is largely dependent upon the balanced relation of the pivot and needle, and the entrance of dust in the needle inclosure as well as the formation of rust upon either needle or pivot is detrimental to the accuracy of the instrument. It is of the greatest importance in an instrument of this kind to prevent the accumulation of rust, either on the pivot or on the needle itself. Rust may easily be occasioned through vapor or the slight moisture in the air, which naturally permeates through the slightest openings in the compass inclosure, such danger being especially present during rainy or foggy weather or, for example, when an instrument is taken into a mine for underground work, where water often drips down directly upon it. My invention effectually eliminates all such danger.

The modifications shown in Fig. 4 are quite similar to the preferred form illustrated in Fig. 3, but of a simpler construction, wherein the plate 17 is discarded, the thumb nut 20 being threaded directly

through the center of the gear 22, which gear has its hub in threaded engagement with a nut 25 locked thereto by a set screw 26 and arranged to overhang and bear upon the top 5 of the protecting device 15. The modifications shown in Fig. 5 comprise a sleeve 26 formed integrally with the protecting member 15, which member is fitted with a removable top 15^a suitably flanged to fit on to 10 the edge of the member 15, as shown, to facilitate the assembling of the parts. The gear 22 in this form is held yieldingly up by a flat spring 27 against a nut 28 threaded onto the top portion of the sleeve 26. The 15 operation of the variation-ring setting gear and of the needle-lifting device in these modifications is substantially identical with that of my preferred form shown in Fig. 3 and need not be further described.

20 Having described my invention, what I claim as new and desire to secure by Letters Patent is:

25 1. A surveyor's compass, having a magnetic needle, a lever to render said needle operative or inoperative, and a variation ring, a substantially dustproof inclosure therefor, containing said needle and ring, means to adjust said variation ring, extending through said inclosure, and separate means, held by said ring adjusting means, to actuate said lever to render the needle operative or inoperative.

30 2. A surveyor's compass, having a magnetic needle, a lever to render said needle operative or inoperative, and a variation ring, a substantially dustproof inclosure therefor, containing said needle and ring, means extending into said inclosure to adjust the variation ring, comprising a hollow

35 sleeve and gear, and a device extending through said sleeve to actuate said lever to render the needle operative or inoperative.

3. A surveyor's compass, having a magnetic needle and a variation ring, a substantially dust-proof inclosure therefor, containing said needle and ring, and having openings through the side walls thereof, means passing through one opening to render the needle operative or inoperative, in combination with means passing through a second opening to actuate and adjust the variation ring, and a single protecting device constructed and arranged to cover both openings and prevent the entrance of dust and moisture therethrough.

4. A surveyor's compass, having a magnetic needle and a variation ring, a substantially dust-proof inclosure therefor, containing said needle and ring, and having openings through the side walls thereof, means passing through one opening to render the needle operative or inoperative, means passing through a second opening to actuate and adjust the variation ring, and a single protecting device constructed and arranged to cover both openings and prevent the entrance of dust and moisture therethrough, in combination with means passing through said protecting device to operate each of said means.

In testimony whereof, I have signed my name to this specification, in the presence of two subscribing witnesses.

CHRISTIAN L. BERGER.
